UNITED STATES PATENT OFFICE.

JOHN P. LINTON, OF MONTREAL, QUEBEC, CANADA, ASSIGNOR TO CUTLER MAIL CHUTE COMPANY, OF ROCHESTER, NEW YORK, A CORPORATION OF NEW YORK.

MAIL-CHUTE.

1,232,058.

Specification of Letters Patent.

Patented July 3, 1917.

Application filed February 14, 1914. Serial No. 818,800.

To all whom it may concern:

Be it known that I, JOHN P. LINTON, a subject of the King of Great Britain, residing in the city of Montreal, in the Province 5 of Quebec and Dominion of Canada, have invented certain new and useful Improvements in Mail-Chutes; and I do hereby declare the following to be a full, clear, and exact description of the same, reference 10 being had to the accompanying drawings, forming a part of this specification, and to the reference-numerals marked thereon.

My invention has reference to mail chutes for use in buildings and of the type consisting 15 of sectional channels with their flat sides secured against the wall of the building or a back carried thereby, the front of such channel consisting of a removable panel, and, as heretofore constructed, having a 20 separately removable strap by which a pair of adjacent panels were locked in place.

Heretofore some difficulty has been experienced with these mail chutes owing to the fact that the locking devices were hinged 25 independently of the removable panels, and have become deranged and damaged by careless operation owing to the leverage on same being so great, on account of the length of the locking strap in proportion to 30 the length of the hinge carrying the same. As a result of this the engagement of the locking devices were not uniform and consequently the lock, although effective, sooner or later might become mutilated and its 35 ready operation interfered with.

Another disadvantage was that if by 40 improper erection the front edges of the channel sections of the chute failed to come into proper alignment, the molding on the panels might be caused to project more at 45 one side than the other, with the result that the hinge bar could not be properly closed and locked, and in installations having more than two panels to complete the chute from floor to ceiling, some difficulty was 50 encountered by the operator in handling the heavy plate glass panels when standing on a ladder or the like and removing the panels for the purpose of clearing a blockage. To 55 overcome the above objections is the object of this invention; and to this end I attach a locking strap rigidly to the top of the lower panel and arrange the locking devices therein midway of its length; co-acting locking

devices being mounted on the chute frame 55 midway of its width and in position to be engaged by the locking devices on the strap. This construction cures all the defects in fitting above mentioned. In order to sustain the upper panel when moved to uncover 60 the stationary chute portion behind it I have pivoted it to the chute frame.

For a full understanding, however, of my invention reference is had to the accompanying drawings forming a part of this specification, 65 in which similar reference characters indicate the same parts, and wherein:

Figure 1 illustrates in front elevation the top of an upper panel, partly broken away, and in vertical section, to illustrate the 70 pivoted connection between the panel and frame;

Fig. 2 is a side elevation thereof, also partly broken away and partly in section;

Fig. 3 is a front elevation of the abutting 75 ends of two panels, illustrating particularly the locking strap partly broken away;

Fig. 4 is a vertical sectional view, taken on line A—A of Fig. 3;

Fig. 5 is a horizontal sectional view taken 80 on line X—X of Fig. 3;

Fig. 6 is a vertical sectional view taken on line B—B of Fig. 3;

Fig. 7 is also a vertical sectional view 85 taken on line C—C of Fig. 1, and

Fig. 8 is a front elevation of the bracket of the chute, with the locking strap and panels removed, the locking bolt appearing in transverse section.

Similar reference numerals throughout 90 the several figures indicate the same parts.

The members of the chute are in the main of the construction usually employed in the installations found in many public and office buildings, and will be first briefly mentioned.

The chute is divided into vertical sections, each comprising chute-members *b* of channel cross-section and having jambs *c* at 100 the opposite sides of its open front to receive the panels as shown in Fig. 5. The lowermost of these chute-members is set into a base resting on the floor, which is not shown as it forms no essential part of my invention. The upper end of the bottom 105 section engages a stationary bracket *e* and terminates at a point adjacent to the lower end of the section above, which latter has its

lower end in engagement with said bracket, and these parts are constructed in the manner which will now be set forth to overcome the defects already pointed out.

5 According to my invention the locking strap 10 is secured rigidly to the top of the bottom panel by means of the legs Z fastened by screws 2 to the molding w.

The strap is in two parts which are suitably secured together, one of oblong form and decorative configuration in cross-section and the other part consisting of a bar 12 with the legs Z cast thereon. A similar bar 12' having upwardly extending legs Z' is 15 secured to the lower end of the upper panel by screws 2'.

The pivot bar 20 has downwardly extending legs V by which it is rigidly connected to the top of the moldings of the upper panel, 20 Fig. 1. The pivots indicated at q are in form of screws threaded through a bracket in the form of a frame, the front bar 25 of which is of reduced depth to accommodate the pivot bar, while the side bars y are wider 25 to carry the pivots above mentioned, and the rear bar is still wider to afford means for fastening by screws 26 to the back board, Fig. 2.

The bracket is fastened to the usual ceiling connection 30 by rivets 31.

The upper panel is hung from the pivots q by means of sockets q' in the bar 20 into which sockets the pivots rotatably engage. The strap 10 attached to the upper end of 35 the lower panel extends, when the panel is in position, in front of the bar 12' at the lower end of the upper panel and prevents forward movement thereof.

In order to obtain access to the chute, the 40 strap 10 is unlocked as usual by a key which, when inserted and turned disconnects the bolt 50 upon the strap from the pairs of locking blocks 57 upon the bracket e. This action releases the lower panel and permits 45 it to be displaced from the chute body by a movement laterally of its surface. The upper panel is also freed when the lower panel is displaced and may be swung outwardly on its pivots q without the necessity of being lifted. This movement of the upper 50 panel is also laterally or transversely of the surface of the panel, as distinguished from a longitudinally sliding movement.

I claim as my invention:

55 1. In a mail chute, the combination with abutting channel sections, and the removable front panels therefor, of a locking strap carried by and rigidly mounted on one of the panels and covering their abutting ends, a 60 locking device located on said strap, a stationary locking bar associated with one of the channel sections located underneath the locking strap and adapted to be engaged by the locking device on the strap.

65 2. In a mail chute, the combination with

abutting channel sections and a transversely extending stationary locking bar associated with one of them having an engaging projection intermediate the ends, of the removable front panels, a locking strap carried by and rigidly mounted on one of them and covering their abutting ends and the stationary locking bar and a locking device located on said strap and engaging the projection to secure the strap and panel in position.

3. In a mail chute the combination with abutting conduit sections arranged in vertical series, each consisting of a stationary member of channel cross-section and a laterally displaceable front panel and a locking strap covering the abutting ends of two panels, of means pivotally securing one of the panels to the chute member covered thereby and means for locking the last mentioned panel to the chute, substantially as described.

4. In a mail chute the combination with abutting conduit sections arranged in vertical series, each consisting of a stationary member of channel-cross-section and a laterally displaceable front panel and a locking strap covering the abutting ends of two panels, of means rigidly securing the locking strap to one panel and arranging such strap to overlap the contiguous edge of the adjoining panel, means for locking the strap to the channel member, and means pivotally securing the said adjoining panel to the chute member covered thereby, substantially as described.

5. In a mail chute the combination with abutting conduit sections arranged in vertical series, each consisting of a stationary member of channel cross-section and a laterally displaceable front panel and a locking strap covering the abutting ends of two panels, of means rigidly securing the locking strap to one panel and arranging such strap to overlap the contiguous edge of the adjoining panel, means for locking the strap to the channel member, and means pivotally securing the opposite end of the said adjoining panel to the chute member carried thereby, substantially as described.

6. In a mail chute of the type described, the combination of a chute member of channel cross-section and a panel forming the front of the chute member, the upper end of the panel being provided with sockets at the sides, and the chute member being provided with pivots rotatably engaging the sockets, substantially as described.

7. In a mail chute of the type described, the combination of a chute member of channel cross-section and a panel forming the front of the chute member, the upper end of the panel being provided with a cross-bar with legs rigidly secured to the sides of the panel such cross-bar having sockets at the

sides, and the chute member being provided with pivots rotatably engaging the sockets, substantially as described.

8. In a mail chute of the type described, 5 the combination of a chute member of channel cross-section and a panel forming the front of the chute member, the upper end of the panel being provided with sockets at the side of the panel, and the chute member 10 being provided with a bracket having mounted therein a pair of pivots rotatably engaging the sockets, substantially as described.

9. In a mail chute of the type described, 15 the combination of a chute member of chan-

nel cross-section and a panel forming the front of the chute member, the upper end of the panel being provided with sockets at the sides, and the chute member being provided with a frame rigidly secured thereto 20 and adapted to accommodate the said upper end of the panel, the sides of the frame being of relatively increased depth and having screws threaded therethrough and serving as pivots rotatably engaging the sockets, sub- 25 substantially as described.

JOHN P. LINTON.
